Primary Examiner — Karen E. Eldridge Powers*Assistant Examiner* — Kimberly Barnes*(74) Attorney, Agent, or Firm* — Cantor Colburn LLP(57) **CLAIM**

We claim, the ornamental design for a display screen with graphical user interface, as shown and described.

DESCRIPTION

FIG. 1 is a front view of a first image in a sequence for the display screen with graphical user interface, showing our new design;

FIG. 2 is a front view of the second image thereof;

FIG. 3 is a front view of the third image thereof;

FIG. 4 is a front view of a fourth image thereof;

FIG. 5 is a front view of the fifth image thereof;

FIG. 6 is a front view of the sixth image thereof;

FIG. 7 is a front view of the seventh image thereof;

FIG. 8 is a front view of the eighth image thereof; and,

FIG. 9 is a front view of the ninth image thereof.

The broken lines in the drawings showing a display screen or portion thereof and features of the graphical user interface illustrate environmental structure that forms no part of the claimed design.

The appearance of the images sequentially transitions between the images shown in FIGS. 1-9. The process or period in which one image transitions to another forms no part of the claimed design.
